CLAIM

The ornamental design for a fabric for sports articles, as shown and described.

DESCRIPTION

FIG. 1 is a top plan view of a fabric for sports articles showing my new design;

FIG. 2 is an enlarged partial cross-sectional view thereof, taken along line 2—2 of FIG. 1;

FIG. 3 is an enlarged partial cross-sectional view thereof, taken along line 3—3 of FIG. 1;

FIG. 4 is a reduced partial perspective view thereof;

FIG. 5 is a reduced partial perspective view thereof;

FIG. 6 is a reduced partial top plan view thereof;

FIG. 7 is a showing of two reduced partial top plan views thereof; and,

FIG. 8 is a reduced partial perspective view thereof.

The broken line showing in FIGS. 1-3 is for the purpose of disclosing boundaries only and forms no part of the claimed design.
